UNITED STATES PATENT OFFICE.

FELIX TAUSEND, OF NEW YORK, N. Y.

ARTIFICIALLY-HEMSTITCHED FABRIC.

Application filed April 22, 1926. Serial No. 103,957.

The present invention is concerned with the provision of an artificially hemstitched fabric, and may be applied to towels, pillow cases, table cloths and various other articles which are frequently hemstitched for decorative purposes.

An object of the invention is to artificially simulate the hemstitching by the use of black threads woven through the fabric in such a manner as to represent hemstitching.

A further object of the invention is to provide a fabric having the appearance of a hemstitched fabric, and yet materially stronger than a hemstitched fabric, inasmuch as the portion of the fabric ordinarily left open by the hemstitching is actually closed by the black threads, so that the strength of the fabric is not impaired.

A further object of the invention is to provide an artificially hemstitched fabric which may be manufactured more cheaply than a hemstitched fabric, and to provide an artificial hemstitch which will be extremely realistic in appearance.

With the above noted and other objects in view, the invention consists in certain novel features of construction and combinations and arrangements of parts as will be more fully hereinafter set forth and pointed out in the claim. The invention may be more fully understood from the following description in connection with the accompanying drawings, wherein—

Fig. 1 is a fragmentary plan view of a towel embodying the present invention.

Fig. 2 is an enlarged detailed plan view showing the artificially hemstitched portion of the fabric of Fig. 1.

Fig. 3 is a transverse sectional view on the line 3—3 of Fig. 2.

While I have shown the invention embodied in a towel, it will be apparent that there is no limit to the number of articles which might be provided with the artificial hemstitch. The towel may be woven of linen or cotton, or other suitable material which is white or light in color. For the most part the weave is conventional, including the usual warp threads 10 interwoven with weft threads 11. This weave is fairly as fine as the ordinary weave in toweling.

In accordance with the present invention, I

substitute for the relatively light weft threads 11 at the point where the artificial hemstitching is to be produced, a series of black or very dark weft threads 12 loosely woven through the warp threads as indicated in Fig. 2. The use of the terms "loosely" and "finely woven" in this case is merely intended to relatively differentiate between the black threads 12 and the light threads 11. Threads 12 are woven in such a manner as to produce a line of rectangular black spaces 13 on the body of the fabric, these black spaces representing the holes usually provided by hemstitching and producing a very realistic imitation of hemstitching. The exact weave of the black or dark colored threads over the light warp threads may of course be somewhat varied in accordance with the particular style of hemstitching which it is desired to reproduce.

As shown in the drawings the dark threads 12 are woven alternately under three warp threads and over four warp threads, so that the towel when viewed from the right side 75 will show a series of oblong black spaces 13 somewhat longer than the white interspaces between them.

It will be apparent that the threads 12 might constitute part of the warp of the fabric, instead of part of the weft, or in some instances might constitute part of both the warp and the weft to represent crossed lines of hemstitching.

In most instances it is only practical to use 85 black threads on either white or very light colored fabric. It will be apparent however, that other dark colored threads might be substituted in certain instances, as for instance where table covers were to be hemstitched, 90 and the threads 12 were of the same color as the surface of the table upon which the cover was to be used.

Various changes and alterations might be made in the general form and arrangement of 95 parts described without departing from the invention. Hence I do not wish to limit myself to the details set forth, but shall consider myself at liberty to make such changes and alterations as fairly fall within the spirit and 100 scope of the appended claim.

I claim:

As a new article of manufacture a towel or the like of light colored fabric having a line

of artificial hemstitching paralleling one of its edges and arranged relatively close to said edge, the line of artificial hemstitching comprising a series of black threads arranged side by side and interwoven with a plurality of series of juxtaposed light colored threads of the fabric proper so that groups of light colored

threads extend at regularly spaced intervals across the series of black thread producing in the fabric a row of alternating black and light areas simulating the openings of a hemstitched fabric.

FELIX TAUSEND.
